BARREL UPENDING DEVICE

Archie T. Stratton, Cleveland, Ohio

Application October 31, 1946, Serial No. 706,881

6 Claims. (Cl. 214—1)

1

The invention relates to lifting devices and more particularly to a device of this character especially adapted for setting barrels and similar articles on end.

It is an object of the invention to provide a simple, inexpensive and easily operated device for upending barrels and the like.

Another object is to provide such an upending device comprising a substantially rectangular frame shaped to receive a barrel or the like in prone position and a substantially L-shape lever pivotally connected to one end of said frame.

A further object is to provide an upending device of this character in which the pivotal connection of the L-shape lever to the end of the frame comprises a pivot pin upon the frame and an elongated slot in the adjacent end portion of the lever providing a sliding pivotal connection which becomes a rigid joint in operation.

A still further object is to provide such an upending device in which means is provided at the angle of the L-shape lever for sliding or rolling contact with the floor or ground.

It is another object of the invention to provide an upending device of the character referred to in which rollers are mounted upon the angle of the L-shape lever for rolling contact with the floor or ground.

The above objects, together with others which will be apparent from the drawings and following description, or which may be later referred to, may be attained by constructing the improved upending device in the manner hereinafter described in detail and illustrated in the accompanying drawings in which:

Figure 1 is a perspective view of an upending device embodying the invention;

Fig. 2 a fragmentary, exploded, perspective view of one end portion of the frame and the adjacent portion of the L-shaped lever by means of which it is manipulated;

Fig. 3 a fragmentary, perspective view of the angle portion of a modified form of L-shape lever provided with a skid device for sliding contact with the floor or ground;

Fig. 4 a side elevation of the improved upending device in normal position upon the floor or ground, a barrel or similar article resting in prone position upon the frame of the device, being shown in broken lines;

Fig. 5 is a view similar to Fig. 4, showing the first operation of upending the barrel, the L-shape lever having been swung upon its pivot substantially ninety degrees relative to the frame and slidably moved upon the pivot pin so as to provide a rigid joint; and,

Fig. 6 a similar view showing the final operation with the barrel standing on end.

Referring more particularly to the embodiment of the invention illustrated in the drawings, the

2

improved upending device comprises a substantially rectangular frame, indicated generally at 10, of proper size and shape to accommodate a barrel or similar article to be upended, in horizontal position.

This frame may be formed of a spaced pair of similar angle irons 11, forming the side members of the frame, and rigidly connected at their opposite ends, as by welding, to the opposite ends 10 of the shorter angle irons 12 and 13 which form the end members of the rectangular frame.

As shown in the drawings the angle iron 13 forming the front end of the frame is of larger dimensions than the angle iron 12 at the other end of the frame. An angle bracket 14 is welded, or otherwise rigidly attached, to the angle end member 13 of the frame 10, and provided with a spaced pair of vertical ears 15 between which is located the slot 16 in the horizontal flange of the angle bracket.

For the purpose of manipulating the device to place a barrel, or other article on end, a substantially L-shape handle is provided comprising the relatively long leg 17 and the relatively short leg 18 which is pivotally connected to the frame in a manner to be hereinafter explained.

In order to form an elongated slot at the end of the short leg 18 of the L-shape lever, a U-shape strap iron, or the like, as indicated at 19 is welded 30 or otherwise rigidly attached thereto, this U-shape member preferably having one leg 20 of greater length than the other so as to connect the same to the side of the leg 18 by welding or the like as shown at 21 in Figs. 1 and 2.

The end of the shorter leg 22 of the U-shape member butts against, and is welded or otherwise rigidly attached to, the end of the leg 18 of the L-shape lever as shown in the drawing, so as to provide a longitudinally disposed, elongated slot 23 at the end of said leg.

Means for affording a rolling or sliding contact of the L-shape lever 17—18 with the floor or ground is preferably provided. As shown in Figs. 1, 2 and 4 to 6 inclusive, where a rolling contact is desired, an axle 24 may be welded or otherwise rigidly attached to the angle 25 of the lever, and a pair of rollers 26 are journaled thereon for rolling contact with the floor or ground.

In Fig. 3 is shown a modified form of L-shape lever provided with means for affording a sliding contact upon the floor or ground. Otherwise the lever may be the same as shown in the remaining figures of the drawings, comprising the relatively long leg 17' and the relatively short leg 18'. At 45 the angle 25' a partial disc 27 is welded or otherwise rigidly attached to the lever in position to contact the floor or ground when the lever is in the positions shown in Figs. 1 and 4 or in Fig. 5.

A pivot pin 28 is adapted to be located through 60 the apertures 29, in the ears 15, and through the

elongated slot 23 at the end of the short leg 18 of the L-shape lever, forming a sliding pivot for the lever upon the frame 10, and a cotter pin 30, or the like, is located through a suitable aperture in the end portion of the pivot pin 28 to retain the pivot pin in position.

In the operation of the truck, to set a barrel or the like on end, the truck is positioned as shown in Figs. 1 and 4 with the rectangular frame 10 flat upon the floor or ground and the L-shape lever in the position as shown, with the rollers 26 resting upon the floor or ground and the long leg 17 in substantially upright position.

A barrel or similar article indicated at 31 in broken lines is rolled upon the frame 10 in prone position, as shown in Fig. 4. The long handle 17 of the L-shape lever is then pulled downward to the position shown in Fig. 5, the rollers 26 rolling upon the floor, toward the frame 10, and the short leg 18 of the lever being raised to substantially upright position, as shown in said figure, raising the adjacent end of the frame 10, and the barrel thereon, to the inclined position as shown.

With this movement of the L-shape lever the pivot pin 28 will by gravity slide back and down to the rear or lower end of the elongated slot 23, in the short leg of the lever, as shown in Fig. 5, so that the under surface of the U-shape strap iron 19 will lie flat against the front of the angle bracket 13, in the manner shown in said figure, locking the lever against movement relative to the frame 10.

With the lever thus locked rigidly relative to the frame it will be obvious that a tremendous leverage may be developed by lifting up the outer end of the lever, fulcruming the frame upon the end member 12 thereof resting upon the floor or ground.

It will be seen that this locking of the lever to the frame is an essential feature of the invention, and although the elongated slot 23, in the U-shape member 19, provides a simple and efficient means for automatically locking the lever to the frame at this point, it should be understood that the invention contemplates any means of producing this locking action within the scope of the appended claims.

The L-shape lever is then pushed upward and forward, or toward the frame 10, pivoting the frame 10 upon the rear end 12 thereof and raising said frame, and the barrel 31 thereon, to the upright position shown in Fig. 6. The lever may then be pulled backward sufficient to disengage the rear end 12 of the frame from the barrel, leaving the barrel standing in upright position upon the floor or ground.

The operation of the device with modified form of L-shape lever shown in Fig. 3 will be the same as above described except that when the device is moved from the position shown in Fig. 4 to that shown in Fig. 5, the disc 27 upon the angle of the L-shape lever will slide upon the floor or ground.

I claim:

1. A device for upending barrels and the like comprising a frame shaped to receive a barrel in prone position, and an L-shape lever pivotally connected to one end of the frame, there being an elongated slot in one end of the lever and a pivot pin upon the frame located through said slot the pin being located at the outer end of said slot when said one end of the lever is positioned in longitudinal alignment with the frame, whereby when said one leg is swung to substan-

tially right angles to the frame the weight of the frame will cause the pin to move down to the inner end of the slot holding the lever rigidly against movement relative to the frame.

5. A device for upending barrels and the like comprising a frame shaped to receive a barrel in prone position, and an L-shape lever comprising a relatively long leg forming a handle, and a relatively short leg pivotally connected to one end of the frame, there being an elongated slot in the end of the short leg and a pivot pin upon the frame located through said slot the pin being located at the outer end of the slot when said short leg of the lever is positioned in longitudinal alignment with the frame, when said short leg is swung to substantially right angles to the frame, the weight of the frame will cause the pin to move down to the inner end of the slot holding the lever rigidly against movement relative to the frame.

15 3. A device for upending barrels and the like comprising a frame shaped to receive a barrel in prone position, and an L-shape lever pivotally connected to one end of the frame, means at the 25 angle of the L-shape lever for contact with the floor or ground, there being an elongated slot in one end of the lever and a pivot pin upon the frame located through said slot, the pin being located at the outer end of said slot when said 30 one end of the lever is positioned in longitudinal alignment with the frame, whereby when said one leg is swung to substantially right angles to the frame the weight of the frame will cause the pin to move down to the inner end of the slot holding the lever rigidly against movement relative to the frame.

4. A device for upending barrels and the like comprising a frame shaped to receive a barrel in prone position, and an L-shape lever pivotally connected to one end of the frame, means at the 40 angle of the L-shape lever for rolling contact with the floor or ground, there being an elongated slot in one end of the lever and a pivot pin upon the frame located through said slot, the pin being located at the outer end of said slot when said 45 one end of the lever is positioned in longitudinal alignment with the frame, whereby when said one leg is swung to substantially right angles to the frame the weight of the frame will cause the pin to move down to the inner end of the slot holding the lever rigidly against movement relative to the frame.

5. A device for upending barrels and the like comprising a frame shaped to receive a barrel in 55 prone position, and an L-shape lever pivotally connected to one end of the frame, means at the angle of the L-shape lever for sliding contact with the floor or ground, there being an elongated slot in one end of the lever and a pivot pin upon 60 the frame located through said slot, the pin being located at the outer end of said slot when said one end of the lever is positioned in longitudinal alignment with the frame, whereby when said one leg is swung to substantially right angles to the frame the weight of the frame will cause the pin to move down to the inner end of the slot holding the lever rigidly against movement relative to the frame.

6. A device for upending barrels and the like 70 comprising a frame shaped to receive a barrel in prone position, and an L-shape lever comprising a relatively long leg forming a handle, and a relatively short leg pivotally connected to one end of the frame, means at the angle of the 75 L-shape lever for contact with the floor or

ground, there being an elongated slot in the end of the short leg and a pivot pin upon the frame located through said slot, the pin being located at the outer end of the slot when said short leg of the lever is positioned in longitudinal alignment with the frame, when said short leg is swung to substantially right angles to the frame, the weight of the frame will cause the pin to move down to the inner end of the slot holding the lever rigidly against movement relative to the frame.
